F. J. WILLIAMS,
REFILLABLE FUSE,
FILED FEB. 15, 1921.

FIG. 1.

FIG. 2.

FIG. 3.

INVENTOR

F. J. Williams.

BY J. Edward Maybee.

ATTY.

UNITED STATES PATENT OFFICE.

FREDRICK JAMES WILLIAMS, OF BUFFALO, NEW YORK.

REFILLABLE FUSE.

Application filed February 15, 1921. Serial No. 445,274.

To all whom it may concern:

Be it known that I, FREDRICK JAMES WILLIAMS, of the city of Buffalo, in the county of Erie, State of New York, United States of America, a citizen of the United States of America, have invented certain new and useful Improvements in Refillable Fuses, of which the following is a specification.

- 10 This invention relates to improvements in electric cartridge fuses in which the fusible element, when blown out, is adapted to be replaced, and my object is to devise a construction which will be very simple and 15 cheap to manufacture, which will have a minimum number of loose parts, and in which the fusible element may be replaced in the least possible time without the aid of tools of any kind.
- 20 I attain my object by means of the constructions hereinafter described and illustrated in the accompanying drawings in which—

Fig. 1 is a view of one form of the device 25 with one half of the casing removed, the end caps being shown in section;

Fig. 2 a longitudinal section of the device;

Fig. 3 an end elevation of the same; and 30 Fig. 4 a side elevation, partly in section and partly broken away, showing another form of my construction.

In the drawings like numerals of reference indicate corresponding parts in the 35 different figures.

The casing of the device comprises two half sections 1 and 2 of a suitable insulating material. In the construction in Fig. 1, I secure to each end of the section 1 a contact member 3 by means of screws 4, while to each end of the section 2 I secure a contact member 5 by means of screws 6. The members 3 preferably are extended to form contact blades. In each contact member 5 is formed 40 an opening 15 preferably rectangular in shape, while on each contact member 3 is formed a projection 7 adapted to be received by the recess 15. The ends of the member 2 will also be provided with a recess behind 50 each opening 15.

It will be understood, of course, that while the projections are shown and described as being formed on the contact members 3, the projections might be formed on the members 5 and the contact members 3 and the section 55 1 provided with the openings or recesses, and

the construction be equally as satisfactory, or, if desired I may, as shown in Fig. 4, dispense entirely with the contact members 5 and form the recesses or projections directly on the section 2.

8 is the fusible member having the usual weakened portion towards its centre. Each end of the fusible member 8 is provided with a rectangular opening adapted for the 65 passage of the projections 7.

In order to properly position the fusible member relative to the members 3, the inner ends of the members 3 are formed with guides 9 adapted to engage in notches 10 70 formed in the sides of the fusible member.

The halves of the casing are secured together by means of the metal end caps 11. These end caps 11 are provided with separated flanges 12 forming in effect notches 75 13 between the flanges. These flanges are of greatest width at their center and gradually narrow down towards each end. The caps are placed in position on the end of the casing over the terminal blades, and 80 then rotated thereon, the blades being provided with notches 14 to receive the flanges 12. It will thus be seen that the more the caps are rotated on the casing, the tighter 85 the engagement of the caps with the terminal blades 3.

The fuse, it will be noted, comprises only five separable parts viz, the two halves of the casing, the fusible member and the two end caps. Further, it will be noted that 90 there are no bolts, screws, or other parts requiring tools to loosen in order to remove a blown out fusible member and insert a new one.

From the above description it will be seen 95 that I have devised a construction which will satisfactorily attain the objects of my invention as set out in the preamble of this specification.

What I claim as my invention is:—

1. In a refillable fuse, the combination of 100 a divided casing; a contact member secured to each end of each part of the casing; a projection formed on one contact member at each end, the other contact member at each 105 end having an opening formed therein to receive said projection; a fusible member having an opening at each end adapted for the passage of said projections; and removable caps adapted to hold the parts of the 110 casing in engagement with one another.

2. In a refillable fuse, the combination of

- a divided casing; a contact member secured at each end of each part of the casing; a projection formed on one of said contact members at each end, the other contact member at each end being provided with an opening adapted to receive said projections; a fusible member having an opening at each end for the passage of said projections; and removable caps engaging one of said contact members at each end and adapted to hold the parts of the casing in engagement with one another.
3. In a refillable fuse, the combination of a longitudinally divided casing; a contact member secured at each end to said casing and having notches formed therein; a fusible member contacting with the contact members; caps enclosing the ends of the casing; and flanges formed on said caps adapted to engage in said notches to retain the caps in position on the casing, said flanges being of varied width and having a cam-like engagement with the contact members.
4. In a refillable fuse, the combination of
- a divided casing; a contact member secured at each end to said casing; a projection formed at each end of the fuse; a fusible member having an opening at each end for the passage of said projections; and having notches formed in its edges; guides formed on the inner ends of said contact members engaging in said notches; and removable caps adapted to secure the parts of the casing in engagement with one another.
5. In a refillable fuse, the combination of a divided casing; a contact member at each end secured to one part of said casing; each of said contact members having a projection therefrom, the other part of the casing having a recess at each end for receiving said projections; a fusible element having an opening at each end through which said projections pass; and removable caps enclosing the ends of the casing.

Signed at Buffalo this tenth day of January, 1921.

FREDRICK JAMES WILLIAMS.
